Primary Examiner — Carol P Rademaker

(57) **CLAIM**

The ornamental design for a bottle, substantially as shown and described.

DESCRIPTION

FIG. 1 is a top, front, right side isometric view of a bottle of the claimed design;

FIG. 2 is a a front elevational view thereof, the rear elevational view being a mirror image except for the unclaimed threads;

FIG. 3 is a right side elevational view thereof, the left side elevational view being a mirror image except for the unclaimed threads;

FIG. 4 is a top plan view thereof; and,

FIG. 5 is a bottom plan view thereof.

The broken lines shown in the drawings are for the purpose of illustrating environmental structure and form no part of the claimed design.
